The ornamental design for a chicken container, as shown and described.

DESCRIPTION

FIG. 1 is a perspective view of a chicken container showing our new design;

FIG. 2 is a top plan view thereof;

FIG. 3 is a bottom plan view thereof;

FIG. 4 is a front elevational view thereof;

FIG. 5 is a back elevational view thereof; and

FIG. 6 is a side elevational view of a chicken container showing our new design, an elevational view of the opposite side being the mirror image thereof.
